UNITED STATES PATENT OFFICE.

ARCHIBALD L. HETTRICH, OF SAN RAFAEL, CALIFORNIA.

DESIGN FOR A LAMP-SHADE.

48,520.

Specification for Design.

Patented Feb. 8, 1916.

Application filed December 1, 1915. Serial No. 64,597. Term of patent 14 years.

To all whom it may concern:

Be it known that I, ARCHIBALD L. HETTRICH, a citizen of the United States, residing at San Rafael, in the county of Marin and State of California, have invented a new, original, and ornamental Design for a Lamp-Shade, of which the following is a specification, reference being had to the accompanying drawing, forming part thereof.

In the drawing, Figure 1 is a side elevation of the lamp shade. Fig. 2 is a view in elevation of the lamp shade, the shade being turned about 60 degrees from the position shown in Fig. 1, and Fig. 3 is a view in ele-

vation of the lamp shade looking in the direction of the plane of Fig. 1.

What I claim is:

The new and ornamental design for a lamp shade, substantially as shown.

In testimony whereof, I have hereunto set my hand this 23rd day of November A. D. 1915, in the presence of the two subscribed witnesses.

ARCHIBALD L. HETTRICH.
